MINIATURE CABINET FOR ELECTRICAL COMPONENTS

Robert D. Veech, 11 Yates Ave.,
Commack, N.Y. 11725

Filed Apr. 22, 1968, Ser. No. 11,564

Term of patent 14 years

Int. Cl. D13—02

U.S. Cl. D26—5

FIG. 1 is a perspective view showing the miniature cabinet for electrical components in exploded relationship with the top of the cabinet removed illustrating the features of the inside of the body of the cabinet, with the hidden inside wall thereof being a mirror image of the inside wall shown, as symmetrical along a longitudinal vertically bisecting plane;

FIG. 2 is a top plan view of the new design for a miniature cabinet for electrical components with the top of the cabinet in place;

FIG. 3 is a view of the outside end of the cabinet which is not visible in FIG. 1; and

FIG. 4 is a bottom plan view.

The vertical and horizontal crossed lines in FIG. 1 and FIG. 2 indicate a surface material covered with small openings as shown, it being understood that the small openings are distributed along the entire cross lined area.

The end of the cabinet opposite to the end shown in FIG. 3 is comprised of the end of the cover as shown in FIG. 1 in place within the end of the cabinet at the left end thereof.

I claim:

The ornamental design for miniature cabinet for electrical components, substantially as shown and described.
